HOOD CAP APPLYING MACHINE

John H. Nelson, Chicago, Ill., assignor to Standard Cap and Seal Corporation, Chicago, Ill., a corporation of Virginia

Application March 24, 1933, Serial No. 662,515

32 Claims. (CL 226—30)

This invention relates to hood cap applying machines, and more particularly pertains to such a machine for applying hood caps of thin flexible material to containers.

One object of the invention is to provide such a machine that will form the hood caps from blanks over the necks of bottles passing through the machine, and secure the caps thereto. Also, wherein the cap blanks are fed to the capping mechanism, instead of feeding the caps thereto like in the ordinary capping machine. Another object of the invention is to provide such a machine having a plurality of connected cap forming and applying heads, each having means for positioning a cap blank, and the heads being arranged to move continuously in a common endless path; wherein the machine will include means for placing bottles into cooperative relation with the capping heads to be capped during a part of said movement of the heads; and wherein the cap blanks are fed to the heads from a common source of supply.

In carrying out one embodiment of the invention, the form disclosed has principally to do with the capping of milk bottles of standard form or the like, wherein the bottles have a protuberance, such as a bead about the necks thereof. In securing the hood caps on such bottles, the cap applying or securing means associated with the capping heads includes mechanism for securing a binder band about the skirt of a hood cap directly under the bead about the mouth of the bottle upon the cap being formed thereover. It is therefore another object of the invention to provide such a machine wherein the binder bands are fed to the band securing mechanism of the capping heads from a common source of supply as the heads travel in their endless path in the machine.

Although the present form of the invention is concerned with the capping of milk bottles, it is not intended that the invention is to be so limited.

Other objects and advantages will become apparent by reference to the specification, claims and the accompanying drawings, in which:

Fig. 1 is a plan view of the complete capping machine with the right hand half of the figure comprising a plan section of Fig. 2, as may be taken on the section line 1—1 of said figure.

Fig. 2 is a front view of the right hand half of the machine with some parts in section, parts broken away and some parts being omitted.

Fig. 3 is a vertical section of a portion of the machine as may be taken on the section line 3—3 of Fig. 2, with parts being broken away.

Fig. 4 is a plan section of a portion of the machine as may be taken substantially on the section line 4—4 of Fig. 2.

Fig. 5 is a vertical section taken substantially on the section line 5—5 of Fig. 4.

Fig. 6 is an enlarged front view of the lower half portion of one of the capping heads showing the neck portion of a bottle inserted therein, and with some parts being broken away.

Fig. 7 is a side view of Fig. 6 with parts in section and parts broken away.

Fig. 8 is a plan section taken substantially on the section line 8—8 of Fig. 7, showing a portion of the capping head in cooperative relation with a part of the binder band feeding means of the machine.

Fig. 9 is a vertical section of a capping head showing the neck portion of a bottle inserted therein, the view being taken generally on the section line 9—9 of Fig. 8.

Fig. 10 is a view similar to Fig. 8 with parts in changed position, parts added and parts omitted.

Fig. 11 is a view similar to Fig. 10 with parts in changed position and parts broken away.

Fig. 12 is a view similar to Fig. 8, but showing the complete bottom portion of the capping head, and more of the band feeding means, also the parts being in changed position to that as seen in Fig. 8. Further, the view being a plan section taken substantially on the section line 12—12 of Fig. 13.

Fig. 13 is a front elevation of the parts seen in Fig. 12.

Fig. 14 is an enlarged detail section taken on the section line 14—14 of Fig. 12.

Fig. 15 is a side elevation of certain parts of Fig. 12 as indicated by the arrow 15 of said figure.

Fig. 16 is a detail view of certain parts of Fig. 13.

Fig. 17 is an enlarged side view of the cap blank feeding means seen in Fig. 2 with parts in changed position.

Fig. 18 is a plan view of Fig. 17 showing parts of the capping head in cooperative relation with the blank feeding means.

Fig. 19 is a section taken on the section line 19—19 of Fig. 18.

Fig. 20 is a vertical section taken on the section line 20—20 of Fig. 18.

Fig. 21 is a vertical section taken on the section line 21—21 of Fig. 18.

Fig. 22 is a plan section taken on the section line 22—22 of Fig. 19 with parts added and parts in changed position.

band material in strip form from which the bands are cut.

Fig. 24 is a side view of a binder band.

Fig. 25 is a perspective of the neck portion of a bottle with the hood cap applied thereon.

The capping machine disclosed is of the rotary type, and since the cap applying mechanism of this invention is shown as applied to container or bottle conveying means which are well known in the art, in describing the machine embodying the invention, I will first dwell somewhat briefly on the bottle conveying means with a general description of the capping mechanism, regarding its cooperative relation with said means.

15 As best seen in Figs. 1 to 5 inclusive, the bottle conveying means includes a continuously moving feed belt 1, in the form of a sprocket chain having cleated links. The upper stretch of the belt is supported horizontally to move toward the center of the machine, upon spaced side rails 2 mounted at their ends and at the discharge end of the belt, on an upright bracket 3 mounted on the base 4, the outer ends of the rails being suitably mounted on the base in a similar manner. 20

25 The feed belt chain passes over an idler sprocket 5 mounted on a stub shaft 6 suitably mounted rotatably in bearings at the outer ends of the guide rails, and at its discharge end the chain passes over a drive sprocket 7 mounted on a driven horizontal shaft 8 rotatably mounted in four spaced bearings 9 on the upright bracket 3. Adjustably mounted on the rails are guide bars 10 on each side of the belt for guiding the bottles to be conveyed thereon.

30 35 The filled bottles 11 are placed on the feed belt at the left end of the machine, as seen in Fig. 1, whereupon they are carried on the belt into cooperative relation with means for spacing the bottles properly on the belt. The spacing of the bottles is regulated by a six-pointed star wheel 12 disposed horizontally to one side of the feed belt so that normally a point thereof extends into the path of the bottles to be turned thereby in passing, said star wheel being mounted on a stub shaft 14 rotatably mounted in a bearing 15 at the end of an extended arm 16 of the bracket 3. After passing said star wheel and on reaching the feed belt discharge end, a bottle becomes engaged in a pocket 17 in the periphery of four pointed, continuously rotating star wheel 18 disposed horizontally above and to one side of the belt discharge end, and comprising spaced sections 18a and 18b. The star wheel 18 is mounted on a vertical shaft 19 rotatably mounted in bearings 20 on the bracket 3. Upon a quarter turn of the star wheel 18 in a counter-clockwise direction, the bottle is transferred from the feed belt onto a turntable 21 whose top surface is in the plane of the feed belt, the bottle being guided onto the table by the curved end portion 22 of the outer guide bar 10, and supported on a shelf 23 extending between the belt and the table.

40 The turntable is mounted on a vertical shaft 24 rotatably mounted at its lower end in a bearing 25 on the base 4, and at its top end is rotatably mounted in a bearing 26 at the hub of a spider frame 27 mounted spaced above the table on the top ends of four vertical uprights 28 spaced about the table and mounted on the base.

45 50 55 60 65 70 75 During transferring a bottle onto the turntable, the star wheel 18 is locked for holding a succeeding bottle to properly position same with respect to the transfer star wheel, wherein the star wheel 12 has a six-pointed ratchet wheel 29 thereunder on its hub which is engaged by a pawl 30 on the

bracket portion 16, and which is operated by a cam 31 on the star wheel shaft 19 at each quarter turn of the star wheel 18.

Upon being transferred onto the turntable, which is caused to turn continuously in a clockwise direction as viewed in plan, the bottles are positioned upon vertically reciprocable bottle supports 35 in the form of hollow cylindrical plungers of which there are six equally spaced about the axis of the turntable, and which are reciprocably mounted in bearings 36 in the table. On receiving the bottles thereon, the support plungers are in lowered position with their closed top ends level with the table, wheretupon as the table is turned, the plungers are moved to raised position, causing the bottles to be raised into cooperative relation with capping heads 37 mounted on and about the central support head 38 which is in turn mounted for vertical adjustment on the turntable shaft, there being a capping head disposed above each support plunger. The support plungers are held in raised position during about one-half revolution of the table, during which time the capping heads are caused to apply the hood caps on the bottles on said plungers. After being capped, the bottles are lowered by the plungers out of cooperative relation with the capping heads shortly before returning to bottle receiving station, and are then transferred onto the upper stretch of a bottle discharge belt 33, 30 whose upper stretch extends in parallelism with the feed belt and spaced from the side of the table in level relation therewith. Partially surrounding the turntable, is a shelf 40 suitably mounted on the uprights, over which the bottles pass in being 35 transferred to the discharge belt. The transferring of the bottles from the table to the discharge belt is effected by a four pointed star wheel 41 whose points pass over the table and belt, and which is mounted on a shaft 42 suitably mounted rotatable in bearings of the bracket 3. An arcuate guide bar 43 is provided to cooperate with the star wheel 41 in transferring the bottles. The discharge belt is of the same type as the feed belt, wherein it passes over an idler sprocket 44 at its discharge end and at its receiving end it passes over a drive sprocket 45 mounted on the outer end of the shaft 8. The shaft 8 is in driven connection with the star wheel shaft 19 through suitable gearing 46, and 40 also in driving connection with the shaft 42 of the star wheel 41 through suitable gearing 47. Said gearing is so arranged to effect the proper timing of the elements controlled thereby.

The bottle transferring star wheel 18 is driven 55 in timed relation with the turntable by means of a spur gear 48 mounted on its shaft 19, and which is in mesh with the spur gear 49 mounted on the bottom end of the turntable shaft under the base 4. The turntable is driven by an electric motor 50 on the base, which, through the intermediation of the pulley and belt connection 51, is in suitable driving connection with the horizontal shaft 52 under the base, on whose end is a worm 53 in meshing engagement with the worm 65 wheel 54 on the bottom end of the turntable shaft.

The bottle support plungers are raised and lowered as they travel with the table by a cam track 55 of arcuate form mounted on the base 70 central with the table axis, the plungers being operated through the intermediation of a lever 56 fulcrumed at one end on a depending portion of the table, and whose other end is in pivotal connection with the plunger by a link 57, and on 75

which end is a roller 58 for engaging the cam track.

The capping heads and instrumentalities controlling their operation will now be described. Said capping heads include a cap forming die head 60 mounted at the bottom end of a depending bracket 61 secured at its top to the central support head 38, said die head is built up of three connected horizontal plates 62, 63 and 64 comprising the top or shelf plate, the mid-plate and the bottom plate respectively. The bottom plate has a slightly depressed top surface portion 65 adjacent the mid-plate to form a cap blank receiving recess or slot 66 open toward the direction of travel of the head for supporting a substantially square cap blank 67 of thin flexible material, such as Cellophane, centrally over a bottle upon its being positioned on a support plunger thereunder, at which position of the bottle said die head is in spaced relation thereabove, and in cooperative relation with a cap blank feeding device for receiving a blank in the recess thereof, said device being generally indicated at 83. In the recess is a leaf spring 68a which lightly holds the blank. In the die head is a vertical bore 69 extending through the plates coaxial with the bottle support plunger, and through which bore the neck of a bottle is projected when raised on the plunger. Below the blank receiving recess, the bore is outwardly flared, as at 70, for guiding the neck of a bottle therein, and in the wall of the bore just above the cap recess are upwardly converging flutes 71 for cooperating to form the cap blank about the bottle neck as same is projected through the bore carrying the blank therewith, whereupon the blank is then formed over the bottle neck and assumes the shape of a hood cap 72, as seen in Fig. 9. Upon being projected into the bore of the die head, the bottle is held non-rotatable therein and positioned so that it extends above the die head with the skirt of the hood cap formed thereover slightly extended into the top end of the bore, whereby its shape is maintained by mechanism which will now be described.

Above the die head, coaxial with the bore therein, is a hollow spindle 73 rotatably mounted at its top end portion in a bearing 74 on the bracket 61. Mounted on the bottom end of the spindle, so as to be relatively rotatable with respect thereto, is an inverted cup shaped head 75 spaced above the die head, and within whose cupped opening 76 the neck of a bottle projected through the die head is snugly received for forming the hood cap tightly over the edge or lip about the mouth of the bottle, and whereby the bottle is held central in the die head bore. For mounting the cupped head, said head has a hollow sleeve portion 77 projecting in the bottom end of the bore of the spindle and which has an annular groove 78 at its top end into which extends a set screw 79 threaded in the spindle wall for holding the sleeve immovable axially. A thrust ball bearing 80 is interposed between the bottom end of the spindle and the cupped head so that the spindle can rotate while the cupped head is held stationary by engagement with a bottle. Within the sleeve 77 of the cupped head is rotatably and slidably mounted a sleeve 81 at the bottom end of which is mounted a bottle engaging disc shaped abutment head 82, snugly receivable in the cupped head but normally spring pressed downward to a position just above the cap receiving recess of the die head, as seen in dot and dash lines in

Fig. 9. The abutment head is resiliently held in lowered position by a coiled compression spring 88 located in the sleeve of the head and interposed between said head and the closed top end 84 of the sleeve 77 of the cupped head. Extending upward from the abutment head is a stem 85 which projects slidably through the top end of the sleeve 77 and at the top end of which is a cap portion 86 for engaging the sleeve end 84 in limiting the downward movement of the head. The abutment head is thus caused to clamp or hold the cap blank on the top of a bottle being projected through the die head whereby the blank is held centrally located on the bottle neck while it is being formed thereover. On the bottom of the abutment head is a rubber ring 87 for securely gripping the blank. Thus the abutment head limits the upward movement of a bottle projecting through the die head and also holds same from turning therein.

The raising of a bottle on a support plunger into cooperative relation with a capping head, causing the formation of a hood cap thereon, occurs during about one-eighth of a revolution of the turntable.

Associated with the capping heads is means, operable upon a bottle being positioned therein, for wrapping a binder band about the skirt of the hood cap formed on the bottle, at which position or station of a capping head during its travel with the turntable, it is disposed in cooperative relation with a binder band feeding device 88a for receiving a band. The band wrapping means of the capping heads includes a twister head 89, later described, which, upon intermittent counter-clockwise rotation of the spindle, as seen in plan, wraps a binder band about the skirt of a hood cap on a bottle as same remains in raised position in the die head. The twister head is mounted on the bottom end of the spindle which is driven to intermittently rotate during its travel with the table by the following means. To this end, a stub shaft 90 extends upward from the spindle in which it is fixedly mounted and on which in turn is mounted a spur gear 91 meshing with a spur gear 92, of equal size, rotatably mounted on a stub shaft 93 secured on the bracket 61. During travel of the capping head with the table, after a bottle is positioned therein, the gear 92 is caused to mesh with, successively, the arcuate gear segments 94, 95 and 96 mounted on the periphery of, and concentric with, a disc shaped support 97 mounted stationary on the bearing portion 26 of the spider frame. The gear segments are so proportioned whereby, on one complete revolution of the turntable, the spindle is caused to make two complete revolutions in a counter-clockwise direction. When not in mesh with gear segments, the gear 92 is locked, for holding the spindle stationary, by means of the Geneva lock ring 98 mounted on the support 97 above the gear segments, which is engaged on its periphery by a four pointed star wheel 99 mounted on the hub of said gear. In the periphery of the ring are recesses 100, 101 and 102 respectively located above the gear segments 94, 95 and 96 for permitting the star wheel 99 to turn when its respective gear is in mesh with gear segments.

Associated with each capping head is means for positioning a binder band in cooperative relation with the twister head, so that upon its rotation, the band is wrapped about the hood cap. Said means includes a band engaging clamp 103 on the shelf plate 62 of the die head, and which

comprises an upright jaw 104 mounted stationary on the plate near its outer edge and parallel with the axis of the table and the die head bore. Cooperating with the stationary jaw is a movable jaw 105 confined for oscillatable movement vertically within the slot 106 in the shelf plate and extending outward from the stationary jaw. The movable jaw is pivotally mounted on, so as to be operated by, a horizontal pin 107 slidably mounted in the bearing bore 108 in the shelf intercepting the slot 106, and wherein the pin extends through a bore 109 in the jaw in which there are helical keys 110, see Fig. 9, received in the helical grooves 111 in the pin, whereby the jaw is operated by reciprocation of the pin. The pin extends beyond the edge of the shelf and has on its outer end, a clevis 112 to which is pivotally connected one end of a horizontal lever 113 centrally fulcrumed at 114 on the shelf plate, which lever is operated by cam means associated with the twister head for moving the pin controlling the movable jaw in releasing same from clamping engagement with the stationary jaw. A compression spring 115 surrounds the pin and is interposed between the clevis thereon and the plate edge for resiliently urging the pin outward in holding the movable jaw in open position.

In general, the cap binder band feeding device includes a feeder head 116 which positions a strip 117, from which the bands are cut, in a horizontal plane and so that the end 117a thereof is held projected tangentially in the path of the stationary jaw of the clamp and in the direction of travel of the capping head, as best seen in Figs. 8 and 12. When the projected strip end is engaged by the stationary jaw during travel of the capping head, the lever 113 is operated to cause the closing of the movable jaw in clamping said strip end to the stationary jaw, whereupon, on continued movement of the capping head, the strip is drawn from the band feeder head, as best understood by reference to Fig. 12. Extending rearwardly of the die head and disposed in the plane of the path of the stationary jaw, is a horizontal arcuate segment 118 mounted on the bracket 61, and whose arcuate edge is concentric with the table axis, and describes an arc substantially intersecting the stationary jaw. In the arcuate edge of said segment is a dovetailed groove 120 in which is received the band strip as it is being drawn from the band feeder head. At the trailing end of the segment 118 is a cutter device 121, later described, which is caused to cut the strip at said end when same reaches the position the capping head assumes as indicated in dot and dash lines in Fig. 12. The cutter device is so located with respect to the clamp whereby, on the cutting of the strip, the binder band 122 is thus formed and supported in the groove of the arcuate segment and held at its forward end in the clamp, the band being of the proper length so as to be wrappable about a hood cap with projected crossed ends, as seen in Fig. 25.

The cutter device 121 includes a vertically movable lever 123 fulcrumed at 124 on the boss 125 of a bracket 126 mounted on the arcuate segment. The lever projects outward and has a depending knife 127 which cooperates with a stationary knife 128 at the end of the band supporting groove when the lever is operated. A coiled spring 129 surrounds said boss with its ends respectively connected to the cutter lever and said bracket for resiliently holding the lever raised with the knife thereon above the path of the band strip. The cutter lever is operated by a

cam 130 which is engaged by a roller 131 on the end of the lever when same reaches the position it is shown in dotted line in Fig. 12, the cam being mounted on a bracket 132 secured to the side of a feeder support head 133 mounted on the top of a vertically adjustable pedestal 134 secured on the base of the machine.

Upon the positioning of a band in a capping head, the twister head is operated to wrap same about the hood cap on the bottle positioned in the head. The twister head includes a sleeve 139 mounted slidably on the bottom end of the spindle and being connected to rotate therewith by means of the key and keyway connection 140 therebetween. Secured to the side of the sleeve 139 is a depending bracket 141 having a bottom end 142 formed arcuate and concentric with the axis of the spindle, and which arcuate end extends close to the top surface of the die head. Located at the leading end of the arcuate segment is a grooved roller 143 disposed normally in the plane of the arcuate segment 118, so as to be in engageable relation with a band held in the clamp, and being fulcrumed on a pin 144 depending from the twister bracket. Located normally in advance of the roller 143 and in the plane thereof, is a tension roller 145 pivotally mounted at the bottom end of a normally depending rocker arm 146 fulcrumed at 147 on the twister bracket. The rocker arm is urged in a turning direction for holding the roller thereon in engagement with the roller 143, by means of a tension spring 148 whose ends are respectively connected to said bracket and the arm. As a bottle is being raised into the die head, the spindle is held stationary with the twister segment initially positioned so that the rollers thereon are considerably in advance of the clamp in clearing the projected end of the band strip when same is being positioned in the clamp, in which position said parts are illustrated in Figs. 6, 7, and 8. On the twister segment is a cam rise 149 which, during the initial position of the twister bracket, engages a roller 150 at the free end of the jaw control lever 113 for causing same to hold the movable jaw of the clamp in open position preparatory to clamping the projected end of the band strip.

At the position of the capping head where the stationary jaw of the clamp engages the projected end of the band strip, in the band feeder head, as seen in Fig. 8, the spindle is rotated one-quarter of a revolution by the engagement of its operating gear 92 with the short gear segment 94, to the position the parts are shown in Fig. 12, whereby the jaw lever is operated to cause the movable jaw to clamp the projected band strip end. On continued movement of the capping head, the band strip is thus drawn from the band feeder device until cut to proper length by the cutter device. On continued movement of the capping head after a binder band has been positioned therein, its spindle operating gear 92 is brought into mesh with the gear segment 95, causing the spindle to make one and one-quarter revolutions, whereby the twister head is caused to wrap the binder band about the hood cap skirt and directly below the bead 151 about the mouth of the bottle, whereupon the twister head reaches its position seen in Fig. 11. During the turning of the twister head in wrapping the band about the cap, the tension roller supporting arm is operated to raise said roller so that it clears the band projected end in crossing thereover as the stationary roller of the head engages the band end, in which position the parts are seen

in Fig. 12. Having crossed over the band end, the tension roller is lowered to hold the band resiliently against the stationary roller as the band is being wrapped about the cap. The tension roller support arm is thus operated by an arcuate cam 152 mounted on the bottom end of the depending bracket 61, said arm having an extended arm portion 153 at whose end is a roller 154 for engagement with the cam.

10 As the binder band is being withdrawn from the guide groove in the capping head when being wrapped about the cap, the trailing end of the band is received so as to be supported in a dovetailed groove 155 in the periphery of the arcuate 10 segment of the twister head. Projecting into the path of the segmental groove on turning of the twister head, is a spring finger 156 mounted on the bracket 61 for forcing the trailing band portion therein.

15 During the wrapping of the band about the cap, the twister head is caused to be raised so that the rollers thereof will ride over the end of the band held in the clamp, then again lowered after passing thereover, whereby the band is 20 wrapped about the cap with its ends crossed, at which position the twister head is seen in Fig. 11. This raising of the twister head also causes the cam thereon to control the movable jaw operating lever, whereby the band end is maintained 25 held in the clamp. For thus raising the twister head, a yoke lever 157 is provided, which is fulcrumed on a pin 158 extending from the bracket 61, and whose yoke portions are provided with opposed rollers 159 engaged in a grooved collar 30 160 secured on the twister head sleeve, said yoke lever being operated at the proper station of the capping head for raising the twister head, by a cam 161 mounted on one of the frame uprights, and which is engaged by a roller 162 on 35 the end of the outer yoke portion of the lever.

40 By means associated with the binder band feeding device, later described, a thin film of moist adhesive is applied to the side of the binder band facing the capping head as it is drawn from said device, for causing the band to adhere to a cap and for joining same at its ends crossed thereover, said adhesive film being shown as applied to the band at 163, see Fig. 24, wherein the film extends to within a short distance from the 45 ends of the band.

45 After the twister head has wrapped the band about the cap so that its ends are crossed and held by the rollers of the head and the clamp, see Fig. 11, the twister head is temporarily held 50 so that the band will adhere to the cap and join at its crossed ends. To insure joining of the crossed ends of the band, a horizontally disposed plunger bar 165 is mounted slidably in a guideway 166 in the twister head arcuate portion so 55 as to extend radial of the die head bore axis. At the inner end of the plunger bar is a presser foot 167 which, upon inward movement of the bar, engages the band at its crossed end portions, the bar being operated by engagement at 60 its outer end with a spring cam 168 mounted on the arcuate cam portion 152, and the bar being held resiliently in retracted position by a coiled spring 169 disposed in a recessed portion 170 of the bar guideway, wherein one end of the spring 65 70 engages a lug 171 on the bar.

75 After the twister head has been held temporarily stationary, causing the securing of the band on the cap, its spindle operating gear 92 engages the arcuate gear segment 96, which causes the spindle to turn one-half of a revolution

80 tion, which returns the twister head to its initial position, as seen in Fig. 8. Upon the return of the twister head to its initial position, the clamp is thus opened to release the band from its connection with the capping head, whereupon the bottle is lowered on the support plunger and out of cooperative relation with the head to be transferred onto the bottle discharge belt of the machine.

85 For preventing the feeding of a band to the capping head in the event a bottle is not positioned therein during its travel with the table, the clamp controlling lever 113 is locked from operating the movable jaw of the clamp. To this end, said lever is provided with a projection 175 180 at its free end which is adapted to engage a vertically positioned rod 176 slidably mounted at its bottom end in a bearing 177 in the top plate of the die head, and whose top end is pivotally connected to the free end of an operating arm 178 185 fulcrumed on the bracket 61 at 179. When a bottle is inserted into the die head, it causes the rod to move to raised position by operating the lever or arm controlling same, whereby, as the twister head is initially turned, the clamp operating lever is released with its projected end portion passing through a slot 180 in the side of the rod, thus allowing the clamping of the band end. In the event a bottle is not present in the die head, the locking rod remains in lowered position with the slot therein just below the projected lever end, whereby the clamp controlling lever is prevented from operating upon the initial turning of the twister head. The locking rod operating lever is operated by the bottle being 200 inserted into the die head through the intermediate of a hollow cylindrical plunger 181 slidably mounted in the bore of the spindle just above cupped head sleeve, which plunger is fixedly connected to a collar 182 slidably mounted 205 on the spindle and in which is a peripheral groove for receiving a roller 183 on the side of the rod control lever, the plunger and collar being connected by the screws 184 extending radially of the plunger and which extend through slots 185 210 215 in the wall of the spindle. For resiliently connecting the plunger to the abutment head so as to be operated by the insertion of a bottle in the die head, the stem of the abutment head extends into the bore of the plunger and is resiliently 220 225 230 connected therewith to cause the raising thereof, by means of a compression spring 186 disposed in the bore of the plunger and interposed between the top end of the stem and the top end of the plunger. The plunger is held in lowered position on lowering of the abutment head, by an inner shoulder formation 187 in the bottom of its bore which is engaged by the shoulder 188 about the cap on the abutment head stem. Thus upon initial upward movement of the abutment 235 240 245 head by engagement with a bottle, the locking rod is moved to raised position, as seen in full lines in Fig. 9, and which elements are shown in their lowered positions in dot and dash lines in said figure.

250 The cap blank feeding device will now be described. On the feeder support head 189 is an upstanding bracket 190 across whose top end is a shaft 191 on which is frictionally rotatably mounted a reel 192 containing a supply roll of cap 255 blank material 193 in strip form. The strip material is drawn from the reel and is guided horizontally in the plane of the cap receiving recesses of the capping heads, so as to be fed therein toward the axis of the turntable, and above the 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

station at which the bottles are positioned on the table and under the heads, within the guideway 201 of a blank strip guide head 202. The guide head is elongated horizontally and is supported 5 at its inner discharge end 203 and at its outer receiving end 204 on the spaced parallel support extensions 205 and 206 respectively, of the feeder support head. Extending along the front side of the guide head is a guide bar 207 mounted at its 10 ends on the support extensions of the support head, and on which guide bar is slidably mounted a strip feeder cross-head 208 which projects under the guide head. The feeder cross-head has up-right front and rear end portions 208a and 208b 15 respectively forming bearings in which are oscillatably, the ends of a horizontal shaft 209 extending directly over and across the guide-head. Mounted on the crosshead shaft are two spaced strip gripper fingers 210 which project through 20 elongated longitudinal slots 211 in the top portion of the guide-head to engage the strip material so as to feed same on reciprocation of the feeder cross-head. In the bottom portion of the 25 guide-head below the guideway, are slots 212 in register with the slots in the upper portion of the head, and in which are slidably received the raised grip portions 213 of the cross-head for cooperating with the gripper fingers in feeding the strip.

The cross-head is reciprocated and the gripper 30 fingers operated to feed the strip material, through the intermediation of a driver head 214 mounted reciprocable on the guide bar and located back of the feeder cross-head. An operable connection is effected between said heads by means of an up-right lever 215 mounted on the cross-head gripper shaft, and whose free end is pivotally connected at 216 to one end of a connecting link 217 whose other end is pivotally connected at 218 to the driver head. Thus as the driver head is moved 35 forward, by driving means later described, the gripper shaft is turned clockwise to apply the grippers, whereupon the cross-head is caused to move forward therewith in feeding the strip material into the path of the cap blank recess of an 40 approaching capping head. Upon the return stroke of the driver head, the gripper fingers are first released from engagement with the strip material before the feeder cross-head is returned therewith. On the bearing portion 208a of the 45 cross-head is a stop pin 219 for limiting the oscillation of the gripper shaft and limiting the amount of play between the driver head and said cross-head. The driver head is reciprocated the 50 proper amount, by means later described, in order that the strip material is intermittently fed the exact amount required to form a cap blank to be positioned in the blank recess of a capping head.

For holding the strip material in fed position on the return stroke of the driver head, a shaft 60 220 extends crosswise over the rear end of the guide head, being oscillatably mounted at its ends in bearings 221 on said head, and on which shaft are mounted two spaced holding fingers 222 spring pressed to extend through slots 223 in the top 65 portion of the head for holding engagement with the strip, the shaft being urged in a turning direction for applying the fingers by a coiled compression spring 224 surrounding the shaft and respectively connected at its ends to the shaft and 70 one of its bearings.

Associated with the strip guide head is a blank forming die device 230, which is operated upon the return stroke of the driver head to cut opposed V shaped cut-outs 231 and 232 in opposite sides 75 of the strip material portion positioned in the

guideway of the head. Thus the cut-outs are so spaced on the strip to form same into connected blank sections 233, the sections being fed to extend projected from the discharge end of the guide head to be cut from the strip at said end upon being received in the blank recess of a capping head. Said die device is in the form of a press which includes a plunger head 234 mounted on the lower 5 end of a plunger shaft 235 reciprocably mounted in a bearing 236 on the bracket 237 secured on the feeder support head. Under the plunger head are mounted male dies 238 and 239 which respectively cooperated with the female die portions 240 and 241 in the bottom portion of the strip guideway in forming the cut-outs, when the plunger is operated. For operating the plunger shaft of the die device, said shaft has a lateral slot 242 in its side in which is received the crank pin extension 238 at the end of a horizontal shaft 244 oscillatably mounted in a bearing 245 of the 10 bracket 237. On the outer end of said shaft is mounted a depending trigger finger 246 on whose upward extended top end is connected the bottom end of a vertically disposed tension spring 247 whose top end is connected to the bracket 237. 15 The trigger finger is thus held, resiliently by the spring, depending in the path of a pin 248 projecting from the side of the connecting link of the driver head, whereupon as said link is moved rearward on the return stroke of the driver head, the 20 trigger finger is operated to turn the crank pin shaft clockwise, causing the lowering of the plunger shaft and the operation of the forming dies. On the forward or feeding stroke of the driver head, no cutting operation is effected by 25 the dies, for the reason that the upper dies are merely raised during said stroke.

For holding the end cap blank portion of the strip material projecting beyond the discharge end of the guide head, so as to be suspended in the 30 path of the cap blank recess of an approaching capping head, the feeder crosshead has a forward arm extension 250 in parallel relation with the guide bar, and which projects beyond the guide head discharge end into an upright end portion 35 251 on which is mounted a clamp 252 for clamping and holding the blank portion at its outer corner toward an approaching capping head. The clamp comprises two movable jaws 253 and 254 positioned respectively above and below the plane of 40 the strip guideway of the guide head, so that their jaw ends may grip the end of the blank portion on initial feeding movement of the feeder head. The upper jaw is mounted on a pin 255 oscillatable in a bearing on the upright bar end, 45 and the lower jaw is pivotally mounted at 256 to said arm end, the jaws being operably connected to operate in unison, by means of the gear connection 257 between their pivoted ends. The 50 jaws are operated to clamp the blank portion upon the initial forward movement of the driver head, through the intermediation of a lever 258, depending from the upper jaw pivot pin, and whose free end is pivotally connected to one end of a link 259 which is pivotally connected at its other end 55 on the pivotal connection 218 of the driver head. The driver head has a feeding stroke slightly greater than the amount required to feed the strip material the amount of a blank, for the reason that, during its stroke, its slight initial 60 movement causes the application of the cross-head gripper fingers and the clamp; then continued movement causes the feeding of the strip material the amount of a blank; at which position the head dwells temporarily until the fed 65 70 75 80 85 90 95 100

blank portion is positioned in the blank recess of a capping head, at which point the driver head continues to move slightly forward to the end of its stroke, causing the release of the grippers and the clamp and also effecting the operation of a cutter apparatus 260 at the discharge end of the guide head for cutting the blank portion from the strip, in which position the parts are shown in Figs. 1 and 2.

10 In carrying out the foregoing functions of the driver head, it is reciprocated by power means, later described, through the intermediation of a horizontally positioned lever 261 located under the guide head and fulcrumed at one end on a pin 262 depending from said head. The lever is connected to reciprocate the driver head through a link 263, whose one end is pivotally connected to the free end of the lever, and whose other end is pivotally connected to the head at 264. At the 20 free end of the lever is a cam projection 265 which, at the end of the feeding stroke of the driver head, engages a roller 266 under the feeder cross head, causing same to move slightly in advance of the driver head to effect the releasing 25 of the grippers and the clamp associated therewith, also, this advance movement of the feeder head causes the operation of the cutter apparatus.

The cutter apparatus 260 comprises a movably mounted knife 267, located below the plane of strip guideway of the guide head and across its discharge end so that the cutting edge 268 of the knife is normally positioned slightly below the end of the guideway, and in register between 35 the opposed V cut-outs of the strip material forming the fed blank portion. The knife is mounted on a vertical slide 269 reciprocably mounted in a guideway 270 of a bracket 271 mounted under the discharge end of the guide head. Above the discharge end of the strip guideway, is mounted a stationary knife 272 for cooperating with the movable knife in cutting the strip. For operating the movable knife upon the final feeding movement of the feeder cross head, said head has 40 a cam formation 273 on its under side which engages and operates a lever 274 mounted on the outer end of a horizontal shaft 275 suitably mounted oscillatably in bearings 276 of the cutter bracket, and on which shaft is a lever 277 whose 45 free end is in pivotal connection with the knife slide for raising the knife thereon in cutting the strip when the lever 274 is operated by the cam.

Through means now to be described, the driver head operating lever 261 is operably connected 50 with the bottle feed star wheel shaft 19, so as to cause the feeding of a cap blank upon each quarter turn of said star wheel, whereupon a blank is positioned in each capping head upon the placing of a bottle thereunder. Mounted on the 55 shaft 19 below the feeder star wheel, is a cam wheel 280, which operates a lever 281, on whose free end is a roller 282 for engaging the cam. Said lever is in spline connection with a vertical shaft 283, rotatably and slidably mounted at its 60 lower end in a bearing 284 on the side of the pedestal 134, and whose top end is rotatably mounted in a bearing 285 on the feeder support head. On the top end of said shaft is a horizontal lever 286, having a sliding pivotal connection 287 at its free end, with the driver head operating lever at its central portion, for oscillating same.

The cam wheel is formed with four uniform cam sections 290, each section comprising a cam depression 291 which, upon rotation of the star

wheel associated therewith, causes the return and feeding stroke of the driver head in positioning a cap blank in cooperative relation with a capping head, and following said cam portion is a cam dwell portion 292 which causes the driver head to dwell so that the fed cap blank is held positioned in the path of the blank recess of the capping head when approaching. Following the cam dwell portion, between same and the depressed cam portion of each cam section, is a short cam rise 293, which causes the driver head to be moved slightly forward to the limit of its feeding stroke, which effects the cutting of the cap blank portion positioned in a capping head recess, and the releasing of same from the gripping means of the feeding device.

In the event a bottle is not positioned in a pocket of the bottle transfer star wheel, means are provided whereby the blank feeder device is rendered inoperative in preventing a cap blank from being fed to the capping head approaching the wheel. Said means includes a horizontally disposed bell-crank lever 295 pivotally mounted at its elbow on an upright pin 296 located to one side of the feed belt, and mounted on an extension 297 of the upright bracket 3. One arm 298 of the bell-crank extends normally in the direction of travel of the feed belt, and is held projected resiliently into the path of a bottle at the discharge end of the belt, by a tension spring 299 connected with the other arm of the bell-crank, and is also movable between the spaced sections of the feeder star wheel. The other arm of the bell-crank extends rearward with a hook formation 300 at its end which is 35 adapted to engage a projection 301 on the cam operated lever 281 in the event a bottle is not present at the discharge end of the feed belt to deflect the bell-crank, and whereby said lever is held from being operated by the cam and thus 40 preventing the operation of the blank feeder device.

In order that no jerky turning motion is imparted to the supply reel 192, during intermittent feeding of the blank strip material, the strip 45 passes from the reel over an idler roll 305 at the lower end of depending lever 306, fulcrumed at its top end on the reel support bracket 190, and which is urged outwardly by a tension spring 307 suitably connected to the lever and the 50 bracket. Thus as the strip material is fed, the jerky motion is taken up by the lever which also serves to maintain constant rotary motion of the supply reel. Above the receiving end of the 55 guide head is also a roll 308, under which the strip material passes from the idler roll into the guideway of the head.

The binder band feeding device 86, including its feeder head 116 and instrumentalities controlling its operation, will now be described. 60 Frictionally mounted on the supply reel shaft 191 and on the side of its support bracket opposite the blank strip supply reel, is a reel 310 containing a roll of the strip material 117 from which the bands are cut. From the reel, the 65 strip passes over a tension roller 311 at the end of lever 312 pivotally mounted on the reel support bracket, then passes or is drawn between two vertically positioned upper and lower guide rollers 313 and 314, to extend flatwise in a horizontal manner into the band feeder head 116. The feeder head comprises a horizontally positioned grooved roller 315, fulcrumed on the cam support bracket 132, over which the band strip 70 passes to be guided into a guideway 316 formed 75

between the end of a finger 317 mounted stationary on the bracket and the free end of a movable finger 318 pivotally mounted on said bracket, wherein the finger is secured to a pin 5 319 rotatably mounted in a bearing 320 of the bracket. The movable finger is resiliently urged toward the stationary finger by a compression spring 321 extending from the bracket to engage an arm 322 mounted on the end of the pin 319.

10 In the wall portion of the band guideway, in the side of the stationary finger, is a recess 323, in which is positioned a pad 324 of felt or other similar material, to which is supplied a liquid adhesive for applying the adhesive film to the side 15 of the band strip as it is being drawn through the guideway in the positioning of a band in a capping head. For supplying the liquid adhesive to the pad, a duct 325 is provided in the stationary finger which is in communication, at the end 20 of the finger, with a flexible conduit 326 extending from a tank 327, mounted on the feeder support head, for containing a supply of the adhesive. In the conduit is a valve 328 for regulating the amount of adhesive to be supplied to 25 the pad.

The movable finger of the band feeder head is operated to withdraw the band strip out of contact with the adhesive supply pad intermittently, so that the adhesive will be applied to the strip 30 in sections, as seen in Fig. 23, which sections are so spaced that upon the strip being cut therebetween, in forming the bands, the adhesive film on the bands extends to within a short distance of the ends thereof, so that the band ends will 35 not adhere to the clamp of the band positioning means of the die head of a capping device, or the band holding means of the twister head thereof. For operating the band feeder head movable finger in the manner stated, the finger is moved 40 outward for a given length of time, by means of a cam 330, mounted on the arcuate segment 118 of a capping head, which engages a roller 331 mounted on the finger end.

Having thus described my invention, I claim:

45 1. In a machine for applying hood-caps of thin sheet material to containers, a plurality of devices arranged about and mounted to rotate around a common axis, each having means recessed toward the direction of travel for receiving and supporting blank caps, and means for shaping the caps from blank form over the necks of containers, and unitary means for feeding the blanks to the devices at a fixed station.

50 2. In a machine for applying hood-caps of thin sheet material to containers, a plurality of devices arranged about and mounted to rotate around a common axis, each having means recessed toward the direction of travel for receiving and supporting blank caps, and means for shaping the caps from blank form over the necks of containers, and unitary means for feeding the material in strip form and cutting same into blanks and arranged whereby the cut blanks 55 are placed in cooperative relation with the devices upon rotation thereof.

55 3. In a machine for applying hood caps of thin sheet material to containers; a plurality of movable devices, each device having slotted means for positioning a cap in blank form in cooperative relation with a container and means for forming same over the container neck; means for feeding cap blanks to the positioning means of said devices at a fixed station during 60 movement of the device; and means for feeding

a binder band to said forming means at a fixed station.

4. In a container hood cap applying machine having a plurality of movable cap forming and applying devices, each device having an open slotted recess for receiving a cap in blank form; unitary means for feeding the cap blanks into the recesses of the devices at a fixed station; and means for feeding a binder band to said devices at a fixed station.

5. In a machine for applying hood-caps of thin sheet material to containers, a plurality of cap forming and applying devices arranged about and mounted to rotate around a common axis, each device having an element horizontally recessed for receiving a cap in blank form, unitary means for feeding the material in strip form and cutting same into blanks and arranged whereby the cut blanks are positioned in cooperative relation with the recesses to be received therein upon rotation of the devices and means cooperating with said horizontally recessed element for forming the blanks on said containers.

6. In a machine for applying hood-caps of thin sheet material to containers, a plurality of capping heads arranged about and mounted to rotate around a common axis, each having an element with a recess open toward the direction of travel of the capping head for receiving and supporting a cap in blank form and cap forming mechanism, and means for feeding a cap blank into the path of each recess so as to be received therein and formed upon a container upon rotation of the capping heads.

7. In a machine for applying hood-caps of thin sheet material to containers, a plurality of capping heads arranged about and mounted to rotate around a common axis, each having an element with a recess open toward the direction of travel of the capping head for receiving and supporting a cap in blank form, and means for feeding the material in strip form and cutting same into cap blanks and arranged whereby the cut blanks are positioned in the path of the recesses so as to be received therein upon rotation of the capping heads.

8. In a machine for applying hood-caps of thin sheet material to containers, a plurality of cap applying devices arranged about and mounted to rotate around a common axis, each device having an element with a recess open toward the direction of travel of the device for receiving and supporting a cap in blank form, and means for feeding the material in strip form intermittently the amount of a cap blank and arranged whereby the fed portion is positioned in the path of a recess so as to be received therein upon rotation of the devices, and means for cutting the strip to form the blank in the recess upon being received therein.

9. In a machine for applying hood-caps to containers, a plurality of cap forming and applying devices arranged about and mounted to rotate around a common axis, each device having an element with a recess open toward the direction of travel of the devices for receiving a cap in blank form, means for feeding the cap blanks in connected strip formation and arranged whereby a blank is positioned in the path of a recess so as to be received therein upon rotation of the devices, and means for disconnecting the positioned blank from the strip.

10. In a machine for applying hood-caps of thin sheet material to containers, a cap forming

- and applying device mounted to move in a fixed path and having an element with a recess open toward the direction of travel of the device for receiving a cap in blank form, a reciprocating feeder head having gripper means for gripping the material in strip form at the end and at a distance inward therefrom greater than a cap blank and adapted to feed the strip portion between the gripping means into the path of the recess so as to be received therein upon movement of the device, and means for cutting the strip to form the blank in the recess upon being received therein.
11. In a machine for forming hood-caps from blanks on containers, a plurality of cap forming heads, a blank feeder head, and means for moving the forming heads and the feeder head into cooperative relation to supply the blanks to the forming heads said blank feeder head having means cooperating therewith to suspend the blanks in the path of said forming heads.
12. In a machine for forming hood-caps from blanks on containers, a rotatable support, a plurality of cap forming heads mounted on the support about its axis, a blank feeder head movable into cooperative relation with the forming heads to supply blanks thereto, and means engaging the advanced end of said blanks to suspend said blanks in the path of said forming heads.
13. In a machine for forming hood-caps from blanks on containers, a rotatable support, a plurality of cap forming heads mounted on the support about its axis, and a blank feeding device arranged whereby the blanks are suspended for cooperative relation with the cap forming heads to supply the blanks thereto.
14. In a machine for applying hood-caps to containers, a plurality of cap applying heads having means for securing a binder band about the cap on a container, a band feeder head, and means for moving the applying heads and feeder head into cooperative relation to supply the bands to the applying heads.
15. In a machine for applying hood-caps to containers, a rotatable support, a plurality of cap applying heads mounted on the support about its axis and each head having means for securing a binder band about a cap on a container, and a band feeder head arranged in cooperative relation with the applying heads to supply bands thereto.
16. The combination with a container hood-cap applying machine having a plurality of cap applying heads arranged about and mounted to rotate around a common axis, each head having means for securing a binder band about a cap on a container including means for positioning a band to be secured, of means for feeding bands to the positioning means of the devices at a fixed station of the heads during rotation thereof.
17. In a container hood-cap applying machine, a plurality of cap applying devices mounted for rotation around a common axis, said cap applying devices having means for wrapping a binder band about a cap on a container including means for clamping one end of the band, means for applying an adhesive film to said band and unitary means for feeding the band and positioning the end thereof into cooperative relation with the clamping means.
18. In a container hood-cap applying machine, a plurality of cap applying heads arranged about and mounted to rotate around a common axis, each head having means for wrapping a binder
- band about a cap on a container, including means for clamping one end of the band, and means for feeding bands from a common source and positioned or arranged whereby the bands are disposed in cooperative relation with said clamping means upon movement of the heads to be engaged thereby.
19. In a container hood-cap applying machine, a plurality of cap applying heads arranged about and mounted to rotate around a common axis, each head having means for securing a binder band about a cap on a container, band forming means associated with each head, and unitary means for feeding band material to the forming means of the heads.
20. In a machine for applying hood caps to bottles, a plurality of cap applying heads arranged about and mounted to rotate around a common axis, a supply for a web of hood material, means for forwarding the web, means to form notches in at least one side of the web, means for severing the web at the notched portion, and means for conforming the severed blank to a bottle.
21. In a machine for applying hood caps to bottles, a plurality of devices arranged about and mounted to rotate around a common axis, a supply for a web of hood material, means for forwarding the web to said devices seriatim, notching cutters operative to form notches in at least one side of the web, means for severing the web at the notched portion, and means for conforming the severed blank to a bottle.
22. In a machine for applying hood caps to bottles, a plurality of cap applying heads arranged about and mounted to rotate around a common axis, a supply for a web of hood material, means for forwarding the web, notching cutters operative to cut notches in at least one side of the web, means for severing the web at the notched portion, and means for applying the severed blank over the mouth of a bottle.
23. In a machine for applying hood caps to containers, a plurality of cap applying heads having means for securing a binder band about the cap on a container, a single means for supplying caps in blank form to said heads, a unitary band feeder head, and means for moving the applying heads and feeder head into cooperative relation to supply the bands to the applying means.
24. In a machine for applying hood caps to containers, a rotatable support, a plurality of cap applying heads mounted on the support about its axis, each head having means for securing a binder band about a cap on a container, a single means for feeding caps in blank form to said heads, and a band feeder head arranged in cooperative relation with the applying heads to supply bands thereto.
25. In a container hood cap applying machine, a plurality of cap applying heads arranged about and mounted to rotate around the common axis, a single means for supplying caps in blank form to said heads, each head having means for securing a binder band about a cap on a container, band forming means associated with said head, and unitary means for feeding band material to the forming means of the head.
26. In a machine for applying hood caps to bottles, a plurality of cap applying devices; a supply for a web of hood material; means for forwarding the web to said devices seriatim; means to form notches in at least one side of the web; means for severing the web at the notched por-

tion to form blanks; and means to actuate said devices to conform the severed blanks to the bottles.

27. In a machine for applying hood caps to bottles, a plurality of cap applying devices; a supply for a web of hood material; means for forwarding the web to said devices seriatim; means to form notches in at least one side of the web; means for severing the web at the notched portion to form blanks; means to actuate said devices to conform the severed blanks to the bottles; and means to apply binder bands to said formed blanks to secure the same on said bottles.

15 28. In a mechanism for mechanically applying skirted caps to bottles, the combination of a plurality of bottle supports mounted to rotate about a common axis; a conveyor adapted to convey bottles to be positioned on said rotary supports; a plurality of cap applying heads, one corresponding to each bottle support; a single source of supply of cap material adapted to be fed to said heads; means to sever a cap blank from said source for each bottle; means to suspend said blank in said head adapted to be applied over the mouth of a bottle; means to cause relative movement between a bottle support and its corresponding capping head; means to conform said blank over the mouth of said bottle 30 and secure the same in place thereon; and means to discharge the capped bottles seriatim from said rotary supports.

29. In a mechanism for mechanically applying skirted caps to bottles, the combination of a 35 rotary table having a plurality of bottle supports mounted thereon and adapted to rotate about a common axis; a bottle conveyor; timing means adapted to transfer bottles from said conveyor to said rotary supports seriatim; a plurality of 40 cap applying heads, one corresponding to each bottle support; a single source of supply of thin cap material adapted to be fed to said heads; means to sever a cap blank from said source for each bottle; said means including a cutting edge 45 over which said thin material is severed into blanks; means to suspend a cut blank in said head adapted to be applied over the mouth of a bottle; means to cause relative movement between a bottle support and its corresponding

capping head; means to conform said blank over the mouth of said bottle and secure the same in place thereon; and means to discharge the capped bottles seriatim from said rotary supports.

5 30. In a mechanism for applying and sealing skirted caps on bottles, the combination of a plurality of cap applying heads; means to rotate said heads about a common axis; means associated with each head to suspend a blank of thin 10 sheet material in position with respect to said head, and above the mouth of a bottle to be sealed; means for causing relative movement between a bottle and its corresponding head; means associated with each head for folding a 15 portion of the blank into skirt form; means to compress said cap into engagement with an exterior surface of the bottle; means to seal said cap on the bottle, and means to discharge sealed bottles from said mechanism.

20 31. In a machine for forming hood caps from blanks on containers, a rotatable support, a plurality of cap forming heads and corresponding container holders mounted on the support about its axis, a source of supply of cap material in 25 strip form, means to sever blanks from said strip material, and a blank feeding device arranged whereby blanks are suspended for cooperative relation with the cap forming heads to supply the blanks thereto.

30 32. In a mechanism for applying and sealing skirted caps on bottles, the combination of a plurality of cap applying heads; means to rotate said heads about a common axis; a source of supply of cap material in strip form; means to 35 sever blanks from said strip material; means associated with each head to suspend a blank of thin sheet material in position with respect to said head, and above the mouth of a bottle to be sealed; means for causing relative movement between a bottle and its corresponding head; means associated with each head for folding a portion 40 of the blank into skirt form; means to compress said cap into engagement with an exterior surface of the bottle; means to seal said cap on the 45 bottle, and means to discharge sealed bottles from said mechanism.

JOHN H. NELSON.
